UNITED STATES PATENT OFFICE.

EMMONS R. BOOTH, OF KIRKWOOD, AND JOHN R. WILLIAMS, OF ST. LOUIS,
MISSOURI.

PAPER-CUTTER.

SPECIFICATION forming part of Letters Patent No. 394,451, dated December 11, 1888.

Application filed April 11, 1888. Serial No. 270,304. (No model.)

To all whom it may concern:

Be it known that we, EMMONS R. BOOTH, of Kirkwood, in the county of St. Louis and State of Missouri, and JOHN R. WILLIAMS, of the city of St. Louis, in the State of Missouri, have invented a certain new and useful Improvement in Paper-Cutters, of which the following is a full, clear, and exact description, reference being had to the accompanying drawings, forming part of this specification, and in which—

Figure I is a front elevation of the machine with sectional rolls, with part broken away to show the thumb or finger gate in the tension-
15 plates that provides a convenient catch-hold of the paper for a redraw and cut, and the coadjutory strap and spiral and tension springs. It also shows a detail of the upper paper roll, whose shaft may have its bearings
20 in a vertical extension of the basement-frame, as in the Patent No. 379,444, issued to us March 13, 1888, or in any other suitable supporting-frame. Fig. II is an end elevation of the machine, and shows the relative course of
25 the paper from two rolls through the second tension-boxing and the rigidly-secured knife that surmounts said boxing. Fig. III is a detail section of a modification, and shows the second tension-boxing, the tension-plates
30 with their individual springs, and beaded heads. It also shows the relative course of the paper from separate rolls and the corrugated knife that surmounts the tension-boxing and severs the paper. Fig. IV is a
35 detail elevation of a modification, showing a detached pedestal that supports the second tension-boxing, the tension-plate, the roller that carries the paper, and the rigidly-secured surmounting knife that severs said paper.
40 Fig. V is an enlarged detail of one of the tension-plates, and shows its pressure-spring and thumb or finger gate that provides a facile catch-hold for the draw end of the paper. Fig. VI is a detail modification of the
45 second tension-springs, in which one spring at each end commands the tension-plates; and Fig. VII is a side elevation of a modification of the machine, in which the vertical pedestal that carries the knife, &c., is cast integral with that which carries the paper roll. It also shows an angular terminal to the shaft

on which the roll rotates, which is seated within a forked tight bearing that projects from the main pedestal and holds said shaft from rotary movement in its seat. 55

This invention relates to devices for holding paper rolls and the manipulation of the paper in the process of cutting; and the invention consists in features of novelty hereinafter fully described, and pointed out in the 60 claims.

Referring to the drawings, in which similar figures of reference indicate like parts in all the views, 1 1 represent the lower sectional rolls, and 2 a portion of the upper paper roll. The rolls are wound around or inclose sleeve bobbins or spools 3, which may either be of length to correspond with that of the roll or may be sectional, being then seated to the required length at each end of the cylindrical aperture within the roll. The paper rolls may be either wound on said spools at the mills, or, especially when sectional spools are used, the rolls may be furnished with open cores and the sectional spools 75 driven in from each end. The spools and rolls are carried on the axle 4, which may either have tight bearings within the spools and run in loose bearings within the forks 5 and the main standards 6 of the frame, from 80 which said forks project, as shown in Figs. I and II, or the axles may have angular terminals 7 to provide a tight bearing within said forked boxing, and then the spool, with the roll it carries, works with a loose bearing 85 around the stationary shaft, as shown in the modification in Fig. VII.

8 represents the platform or base-plate, of either wood or metal, to which the flanged feet 9 of the standard (which is preferably of 90 cast-iron, but may be of any other suitable material) is firmly secured by screw-bolts 10.

11 is the top or cap plate, which may be of either wood or metal and secured to the standards by any suitable means. The upper roll, 95 2, may be either supported to a vertical elongation of the standard 6, as shown and described in the patent issued to us March 13, 1888, No. 379,444, or it may be supported on bracket-bearings, as also shown and described 100 in said patent, or by any other suitable means, as no novelty is claimed for the means of sup-

porting said upper roll other than that by which the lower roll is supported.

12 represents the flanged heads of the main standards 6, to which the top or cap plate is secured, as stated, by any suitable means. The front portions of said heads have enlarged projections that are surmounted by inclined edges 13, to which are secured the knives 14, which are fastened to said inclines by screws 15, or by any other suitable means, and together form a box bearing-chamber, 16, in which is carried the shaft 17, that has its bearings (either loose or tight) in the corresponding projecting flanges that constitute the side walls of the boxing, and the said shaft carries a loose rotary sleeve, 18, that forms a combined guide and anti-friction roller. Within said boxing also work the second tension-plates, 19, whose number—one, two, or more—corresponds with that of the paper-rolls. The said tension-plates bead around and have tight bearings on the rods 20, that have loose bearings in the projecting flanges that form the side walls of said box bearing-chamber.

The tension-plates are preferably looped around to form beads 21 at their free ends, and the lower one, and, when required, the upper also, is provided with a spring, 22, at each end, whose fast end is rigidly attached to the tension-plate, and it winds spirally around the shaft that carries said tension-plate and is held to its spring action by the stay-pin 23. The upper tension-plate, and the lower one also, when preferred, is provided with a thumb or finger gate, 24, to facilitate the grasping of the ends 25 of the paper to draw it out ready for cutting.

26 represents washers that are mounted on the shaft or shafts that carry the rolls and press against the ends of said rolls under the impingement of the spiral springs 27, that are also mounted on said shafts and are backed up by the main standards of the frame and the forks 5, that project therefrom to exert an end tension on said washers 26, and by their means on the rolls.

28 represents strap-springs that are secured to the inside of the flanged heads of the main standards by rivets or screws 29 and press against the aforesaid washers 26 beyond the action of the spiral springs, to re-enforce the tension of said spiral springs as coadjutants thereto.

55 It will be seen that as this system of double spring-tension is, unlike the peripheral tension in common use, exerted solely on the ends of the rolls, and that not far removed from their center, it follows that an even tension is always exerted on the rolls, and does not vary, as does the peripheral tension, when from the near exhaustion of the roll the pressure of the peripheral spring is also nearly or quite exhausted.

65 In Fig. III is shown a modification in which the box bearing-chamber wherein the second tension-plates, &c., operate is detached from

the roll-carrier frame and secured by screw-bolts 30 to the counter or other convenient position handy to the clerk or operator that handles the paper. Sometimes there is not room for the rolls and their supporting-frame on the counter of busy retail establishments, in which case the frame, with its rolls, can be located in any suitable position out of interference with the movements of the clerks, and either be elevated above the counter or placed down beneath it; or, as shown in said figure, by the direction from which the paper arrives, one roll may be located above the counter and the other be placed beneath it. In this modification we have also shown a modification of the knife, which is provided with a corrugation, 31, to stiffen the blade, which also carries a bead, 32, on its upper edge that has the double function of re-enforcing the attachment of the blade and guiding the approach of the paper from the upper roll.

It will be seen that in the modification in Fig. III, as also in those of Figs. IV and VII, the second tension-plates operate from beneath the paper against which they press; but we do not confine ourselves to that position, for, as shown in Figs. I and II, the lower tension-plate may be and is located above the paper, and in either case they effect the same purpose—viz., hold the paper that has just been withdrawn from the roll while it is being cut, and to hold the stub to present a convenient catch-hold for the next withdrawal.

In Fig. IV is shown another modification, for use also in positions removed from the rolls, in which the aforesaid box bearing-chamber 16 surmounts an independent pedestal, 33, whose flanged foot may be secured to the counter or other suitable position by the screws 10. In this modification is also shown an anti-friction-roller guide, 34, whose pivot-rod works in loose bearing in the sides of the boxing. The paper is shown in this figure in full line descending from an elevated roll and in dotted lines from a roll on the same level. In the figure showing this modification, as also in Fig. VII, single tension-plates only are shown; but we do not so confine ourselves, for twin tension-plates that operate on paper delivered from two rolls may be used, as shown in Figs. I, II, III, and VI.

In Fig. VII is shown a somewhat similar modification to that described above in Fig. IV, in which the pedestal 33 is cast integral with the main standard that carries the roll or rolls. In this figure is also shown a modification of the second tension-spring, in which the stay ends 36 of the springs rest on ledges 37, that project inward from the sides of the boxing 16, and thus support the spring and back it in its action on the tension-plate in the place of the stay-pin 23.

We have shown the pedestal 33 in a vertical position in this modification; but it may be placed in an inclined position, the inclination verging either to or from the roll or rolls.

In Fig. VI is shown another modification of

the tension-springs, in which a single spring, 38, enforces the tension of both the upper and lower second tension-plates.

It will be seen that we show sectional rolls 5 of the same width as the lower rolls and a single long roll above; but their relative positions may be reversed when preferred, and the sectional rolls may be of diverse widths.

We have shown two sectional rolls on one 10 axle and a single roll; but we do not confine ourselves to any definite number of rolls, for it is evident that the especial features of our invention can be applied to a larger or smaller number of rolls than those shown.

15 When there are sectional rolls on one shaft, an anti-contact washer, 38, is mounted on the shaft between said rolls.

We have shown and described coadjutant 20 spiral and strap end-tension springs; but we may, especially with small rolls, use only the spiral or the strap springs, as may be preferred, without the re-enforcement of the co-operative springs.

It will be seen that the beads 21 at the free 25 ends of the second tension-plates, besides acting as anti-friction terminals to guide to a free passage of the paper on a draw, also direct the right presentation of the paper for a convenient catch-hold for a redraw.

30 We claim as our invention—

1. In a roll-paper holder and cutter, the combination of the paper roll, the bobbin-spools within said roll, the axle that carries the roll, and standards in which said axles 35 have bearings, the tension-washers located around said axle and against the ends of the roll, and the end-tension spiral springs 27, substantially as and for the purpose set forth.

2. In a roll-paper holder and cutter, the 40 combination of the sectional and single paper rolls, the axle that carries the rolls, the tension-washers mounted on said axle and against the outer ends of the rolls, and the strap tension-springs 28, that press against said washers and exert an end tension on the 45 rolls, substantially as and for the purpose set forth.

3. In a roll-paper holder and cutter, the combination of the paper roll, its axle, the 50 tension-washers mounted on said axle, the spiral and strap springs that press against said washers and exert an end tension on the roll, and the spring-actuated second tension-plates, 19, provided with beads at their free 55 ends to facilitate the passage of the paper when it is drawn from the roll to give it a right presentation for a redraw, substantially as and for the purpose set forth.

4. In a roll-paper holder and cutter, the 60 combination of the sectional and single paper rolls and axles, the standards with forked projections, in which said axles have their bearings, the end-tension washers, the spiral and strap springs that press against said washers 65 and exert an end tension on the rolls, the sec-

ond spring tension-plates with beaded free ends, the finger-gate 24 in said tension-plates, the single knife 14, that cuts the paper of all the rolls, and the bead 32 beneath the upper edge of said knife, that provides a guide for 70 the paper on its passage from the roll to the knife, substantially as and for the purpose set forth.

5. In a roll-paper holder and cutter, the combination of the sectional and single paper 75 rolls, the axles that carry the rolls, and forked standards in which said axles have their bearings, the tension-washers, and end-tension spiral and strap springs, the second tension-plates with beaded free ends, the single 80 straight-edge knife with a corrugated blade to stiffen the same, that cuts the paper from all the rolls, the anti-contact washer 38, that separates the sectional rolls, and the rotary sleeve-roller 18 and guide-roller 34, that carry 85 the paper on the draw, substantially as and for the purpose set forth.

6. In a roll-paper holder and cutter, the combination of the main standards 6 of the roll-carrier frame, the forked projections 5 90 from said standard, that form bearings for the axles, the box bearing-chamber 16, the second tension-plates and their actuating-springs that occupy said chamber, and the single knife with a straight edge and corrugated blade, that cuts the paper of all the 95 rolls, substantially as and for the purpose set forth.

7. In a roll-paper holder and cutter, the sectional and single rolls, with means for end 100 tension against said rolls, the second tension-plates with beaded free ends, that work within the chamber 16, the spring 22, that actuates said tension-plates, whose stay end is backed to its work by the ledges 37 of said chamber, 105 and the single knife whose blade is stiffened by corrugations, said knife cutting the paper from all the rolls, substantially as and for the purpose set forth.

8. In a roll-paper holder and cutter, the 110 means for end tension against the rolls, comprising the washers that press against the ends of the rolls, the spiral springs that impinge against said washers, the standards and their forks 5, that constitute the backing for 115 said tension-springs, and the strap-springs 28, that exert pressure against said end-tension washers outside said spiral springs, substantially as and for the purpose set forth.

9. In a roll-paper holder and cutter, the 120 sectional and single rolls and the single straight-edge knife whose blade is stiffened by corrugations, and said knife cutting the paper from all the rolls, substantially as and for the purpose set forth.

EMMONS R. BOOTH.
JOHN R. WILLIAMS.
